UNITED STATES PATENT OFFICE.

HENRY SMITH, OF SALEM, MASSACHUSETTS.

IMPROVEMENT IN FISHING-SEINES.

Specification forming part of Letters Patent No. 124,635, dated March 12, 1872.

Specification of an Improved Fishing-Seine, invented by HENRY SMITH, of Salem, in the county of Essex and State of Massachusetts.

The "purse-seine," so called, now in common use, is a single sheet of netting some fifty fathoms long by twenty fathoms wide, more or less, having buoys on one edge and weights upon the opposite edge, by which it is sunk edgewise into the water, the weights upon one edge and the floats or buoys upon the other tending to keep it in nearly a vertical position in the water, it being extended to its greatest length in nearly a straight line by means of lines from either end, which are operated for the purpose by the boat's crew. Other lines, running through the bottom edge are operated at the proper time to "purse" up the lower part of the sheet of netting into a sort of pocket to prevent the fish from darting or diving below the edge of the seine and escaping, as is often the case in mackerel fishing.

In fishing with large seines the process of pursing the seine is necessarily a slow one, and it often happens that a large part of and sometimes the whole school escape before it can be accomplished, in which case the labor has all to be done over again. To remedy the difficulty just mentioned is the object of my invention; and it consists in constructing the seine in the form of a bag, having a bottom, around which are secured weights for sinking the same to the proper depth, the upper edge or mouth of the bag being provided with buoys or floats around at least one-half its circumference, while the other portion thereof is provided with weights, by which it may be sunk to the proper depth—say five fathoms, more or less—to allow the school of fish to pass over it, so that when they touch the other side of the bag-seine and dart downward they cannot escape until they rise again to pass over the sunken edge of the bag. It also consists in a peculiar arrangement of lines by which the two parts or sides of the bag are separated, the mouth and bottom of the seine is expanded, and the sunken side is raised to the surface of the water when the school of fish are fairly in the toils.

In the drawing, Figure 1 is a plan showing the seine and arrangement of lines and boats for operating the seine when the seine has just been sunk. Fig. 2 is a plan of the same with

the seine expanded; and Fig. 3 is an elevation of the same, showing a portion of the front side sunk preparatory to receiving a school of fish.

A is the back, and A' the front side of the seine, the same being united at their ends to the vertical cords *a a*. B is the bottom united to the sides by means of the cord *b*, on which are secured at intervals the weights *c c*, for the purpose of sinking the seine. Around the top or mouth of the seine is run the cord *d*, on which are secured the buoys or floats *e e e* and the weights *f f*. At each end of the seine the lines *g g* are attached to the cord *d*, and extend to the boats *h h*, where the slack or middle portion is coiled away, the opposite end of the same lines being secured to the front side of the seine near the weights *f f*, and lead to the boats *h h*, as shown at *i i*. Another line, *i' i'*, is secured to the cord *d* between the weights *f f*, the other end of which is secured to the line *i* at a suitable point between the attachment of the line *i* to the seine and the boat with considerable slack therein. To the cord *d* on the back side of the seine are secured the lines *j j*, which lead thence to the boats *h' h'*, where they are secured and are operated for the purpose of opening the mouth of the seine, as shown in Fig. 2. The lines *k k*, one end of each of which is secured to the cord *b* in the bottom and leads to the boats *h' h'*, are used to expand the bottom or to hold the two sides *A* and *A'* apart at the bottom to give space for the fish, as also shown in Fig. 2.

The operation of my improved seine is as follows: The seine is sunk into the water nearly in a vertical line, and extended in nearly a straight line between the boats *h h*, as shown in Fig. 1, in which position it is maintained by the lines *g g*, until it is placed in the right position to receive the school of fish when the lines *j j* and *k k* are hauled in by the men in the boats *h' h'*, and the two sides of the seine are separated, as shown in Fig. 2. The back side is held up even with the surface of the water by the floats or buoys *e e e*, while a portion of the front side is made to sink to a suitable depth to allow the fish to pass over, as shown in Fig. 3. When the fish have passed over the sunken front side the lines *i i* are drawn in by the men in the boats *h h* raising the weights *f f* until the lines *i' i'* reach the

boats, when the slack in them is drawn in raising the front side to the surface of the water when the fish are securely inclosed in a bag net from which there is no escape.

I do not claim, broadly, a seine made in the form of a bag-net, for I am aware that such have been used before; but

What I claim as new, and desire to secure by Letters Patent of the United States, is as follows:

1. A seine made in the form of a bag, and having the floats *e e* and weights *ff* secured thereto around its mouth, in such a manner that a portion of the mouth of the bag may be sunk below the surface of the water by the weights, while the remaining portion is kept even with the surface of the water by the floats, substantially as described.

2. In combination with a seine made in the form of a bag and provided with the buoys *e e* and weights *ff*, the lines *jj* for opening the mouth of the seine, substantially as described.

3. In combination with a seine made in the form of a bag, the lines *kk*, for expanding the bottom, substantially as described.

4. In combination with a seine made in the form of a bag and provided with the weights *ff* and the floats *e e*, the lines *ii* and *ii'*, for the purpose of raising the sunken side of the seine, substantially as described.

Executed at Boston this 18th day of November, 1871.

HENRY SMITH.
